(57) **CLAIM**

The ornamental design for a UV disinfection reactor, as shown and described.

DESCRIPTION

FIG. 1 is a top, rear, left isometric view of an UV disinfection reactor;

FIG. 2 is a top, front, left isometric view thereof;

FIG. 3 is a bottom, front, left isometric view thereof;

FIG. 4 is a bottom, rear, right isometric view thereof;

FIG. 5 is a top view thereof;

FIG. 6 is a bottom view thereof;

FIG. 7 is a left side view thereof;

FIG. 8 is a right side view thereof;

FIG. 9 is a front view thereof; and,

FIG. 10 is a rear view thereof.

The features shown in broken lines are for illustrative purposes only and form no part of the claimed design.

1 Claim, 9 Drawing Sheets
